(57) **CLAIM**

I claim the ornamental design for a faucet, as shown and described.

DESCRIPTION

FIG. 1 is an upper perspective view of the faucet showing my design.

FIG. 2 is a side view thereof, wherein an opposite side view is a mirror image thereof;

FIG. 3 is front elevation view thereof;

FIG. 4 is a back elevation view thereof;

FIG. 5 is a top plan view thereof; and,

FIG. 6 is a bottom plan view thereof.

The broken away showing of the supply lines indicates that they are of indeterminate length.
